J. F. MOCK

DOUBLE TUBE

Filed May 28, 1925

UNITED STATES PATENT OFFICE.

JOHN F. MOCK, OF PHILLIPSBURG, NEW JERSEY, ASSIGNOR TO INGERSOLL-RAND COMPANY, OF JERSEY CITY, NEW JERSEY, A CORPORATION OF NEW JERSEY.

DOUBLE TUBE.

Application filed May 28, 1925. Serial No. 33,398.

This invention relates to fluid actuated rock drills, but more particularly to rock drills of the hammer type which employ concentrically arranged water and air tubes for conveying water and air to the drill for cleansing the drilled hole.

One object of this invention is to produce a mixture of air and water within a rock drill of the hammer type for cleansing the 10 drilled hole by arranging the water tube concentrically within an air tube.

Another object is to enable concentrically arranged air and water tubes to be secured within a rock drill in an improved and 15 simplified manner, and a further object is to improve generally in devices for supplying cleansing fluid through a rock drill to a drilled hole.

Other objects will be in part obvious and 20 in part pointed out hereinafter.

The invention consists of the combination of elements, features of construction and arrangement of parts having the general mode of operation substantially as hereinafter described and more particularly pointed out in the appended claims and illustrated in the 25 accompanying drawing, in which

Figure 1 is a side view in elevation and partly in section of a rock drill of the stoper type, and

Figure 2 is a sectional view in elevation of a portion of a rock drill showing the manner in which the air and water tubes are arranged with respect to each other and 30 also showing the securing means employed for holding the tubes.

Referring to the drawing, the invention is shown embodied in a rock drill of the stoper type in which a cylinder A and a 40 front head B are held in position by the usual side bolts (not shown). A back head C forms a closure for the cylinder A and is held in operative position with respect thereto by a pin D.

Disposed within the cylinder A is a reciprocating hammer piston E. In this instance, an anvil block F is arranged in advance of the piston E for transmitting the blows of the piston to a hollow drill steel G inserted within the front head B. A front cylinder washer H is interposed between the cylinder A and the front head B for centralizing said cylinder and front head and has a bore J

which serves as a seat and a guide for the anvil block F.

The feeding element of the machine, in this instance, comprises a feed cylinder K. A piston rod L slidable within said cylinder supports at its outer end a rock engaging pointer O and at the opposite end a piston head (not shown). Interposed between the back head C and the feeding cylinder K is a head block P, and bolts Q arranged on opposite sides of the machine and provided with suitable nuts R secure the feeding cylinder K to said head block.

Pressure fluid is admitted into the machine through a suitable connection S secured to the back head and admission of pressure fluid to the cylinder is controlled 70 by a throttle valve T having a throttle lever U for manipulating said valve.

In this instance, the cylinder A and the piston E, forming the percussive element of the machine, are of the type in which constant pressure is maintained in the rearward end of the cylinder. The distribution of pressure fluid admitted through a passage V into said cylinder is controlled by a rearward extension W of the piston E. Said extension W controls the admission of pressure fluid to the rearward and front faces of the piston E through supply passages X and Y respectively. The pressure fluid is exhausted from the cylinder A through an 85 exhaust port Z.

Any suitable means may be provided for rotating the drill steel within the drill hole. In this instance, a rotation handle b is secured to the back head C and is adapted to 90 be grasped by the operator for rotating the machine and drill steel as a unit.

In accordance with the present invention, a pair of tubes c and d are preferably arranged concentrically with respect to each other and extend through the machine for conveying cleansing fluid to the drill hole. The outer tube c in this instance serves to convey water admitted into the back head through a connection e and is of sufficiently 95 larger cross sectional area than the tube d to form a passage f between its bore and said tube d. A restricted portion g is formed on the tube c at its forward end. The tube d is provided with a collar h near 100 its rearward end and preferably extends 105

through the tube *c* to a point near the restricted portion *g*. In this instance, a passage *j* provides communication between the tube *d* and the throttle valve *U*. The passage *j* is so arranged with respect to the passage *V* leading to the cylinder *A* that fluid is admitted to said tube simultaneously with the admission of pressure fluid to the cylinder *A*. Pressure fluid for actuating the feeding element is admitted through a passage *k* and the passage *k* preferably communicates with the throttle valve at a point near the opening of the passage *j* so that when the throttle valve *T* is moved to admit pressure fluid to the cylinder *A* and the tube *d*, pressure fluid will be simultaneously admitted to the feeding element.

In order to secure the tubes *c* and *d* within the head block *P*, a water tube cap *o* is arranged about the tube *c* and is provided with suitable screw threads to enable said cap to be screwed into the head block. In this instance, the cap *o* is provided with a bore *p* which is preferably of substantially the same diameter as a collar *q* carried by the tube *c*. A packing ring *r*, which may be of rubber or other suitable material, is disposed within the bore *p* forwardly of the collar *q* of the water tube *c*, and is adapted to engage said collar so that when the cap *o* is screwed into the head block *P*, the tube *c* is forced rearwardly into the head block. In order to hold the tube *d* firmly in position, the end of the tube *c* abuts the collar *h* of the tube *d* and as the tube *c* is forced rearwardly, the collar *h* is pressed firmly against a packing *s* inserted into a bore *t* formed in the head block *P*. Leakage of fluid between the head block *P* and the cap *o* is prevented by a suitable gasket *u*.

In order to admit water into the tube *c*, a plurality of ports *v* are formed in the wall of said tube between its rearward end and the collar *q*. The ports are so arranged that when the tube is pressed into position, they will be in direct communication with the water connection *e*.

In the operation of the machine, assuming that the throttle valve *U* is in the position shown in the drawings and that water is admitted to the tube *c*, the air passing through the tube *d* will intermingle with the water at the forward end of said tube and thus augment the water pressure for carrying the cuttings from the drill hole.

This invention has been found to be efficient in operation, it is inexpensive to manufacture and its advantages reside in the fact that the rearward ends of the tubes may be perfectly sealed against leakage of fluid to the cylinders, and owing to the flexibility of the packings which form a seat for the tubes, the necessity of constant inspection on the part of the operator regarding leakage is eliminated.

I claim:

1. In a fluid actuated rock drill, the combination of a percussive cylinder with a feeding cylinder, a back head for the percussive cylinder, a head block forming a closure for the feeding cylinder, a water tube supported at one end within the head block extending through the back head and the percussive cylinder into a drill steel, a collar near one end of said tube, an air tube supported at one end within the head block and extending through the water tube, a collar near one end of said air tube to abut the end of the water tube for preventing movement of the air tube in one direction, and means arranged forwardly of the collar on the water tube to cooperate with the second said collar and with the head block for securing the tubes in position.

2. In a fluid actuated rock drill, the combination of a percussive cylinder with a feeding cylinder, a back head for the percussive cylinder, a head block forming a closure for the feeding cylinder, a water tube supported at one end within the head block and extending through the back head and the percussive cylinder for conveying water to a drill steel, a collar near one end of said tube, an air tube supported at one end within the head block and extending through the water tube, a collar near one end of said tube, the collar on the air tube to abut the end of the water tube for preventing movement of the air tube in one direction, a packing about the air tube and abutting the collar on said tube, and a cap to receive the packing and the air tube collar for holding the tubes against longitudinal movement.

3. In a fluid actuated rock drill, the combination of a percussive cylinder with a feeding cylinder, a back head for the percussive cylinder, a head block forming a closure for the feeding cylinder, a water tube supported at one end within the head block and extending through the back head and the percussive cylinder for conveying water to a drill steel, a collar near one end of said tube, an air tube supported at one end within the head block and extending through the water tube to convey air for augmenting the pressure of the water, a collar near one end of said tube and abutting the end of the water tube for preventing movement of the air tube in one direction, a packing about the air tube and abutting the collar on said tube, a cap screwed into the head block to receive the packing and the air tube collar for holding the tubes against longitudinal movement, and means for preventing leakage of fluid from the head block into the cylinder.

In testimony whereof I have signed this specification.

JOHN F. MOCK.
